UNITED STATES PATENT OFFICE.

FRED W. AYER, OF BANGOR, MAINE, ASSIGNOR TO THE EASTERN MANUFACTURING COMPANY, OF SAME PLACE.

DIGESTER.

SPECIFICATION forming part of Letters Patent No. 624,608, dated May 9, 1899.

Application filed January 9, 1899. Serial No. 701,609. (No model.)

To all whom it may concern:

Be it known that I, FRED W. AYER, of Bangor, county of Penobscot, and State of Maine, have invented an Improvement in Digesters, 5 of which the following description, in connection with the accompanying drawings, is a specification, like letters on the drawings representing like parts.

The present invention relates to a digester 10 of the kind commonly employed for making wood-pulp, and is mainly embodied in a novel construction and arrangement of the lining for the digester-retort, whereby the metallic body or shell is protected from the action of 15 acids and gases which are used in reducing the wood to pulp.

In accordance with the invention the metallic body of the digester is first provided with a lining of brick laid thereon, the said 20 lining being so arranged that each brick is supported directly by the metal shell, being in contact therewith, while a space is left between the said lining and the surface of the metallic shell, there being a projecting support 25 for each brick of lesser area than that of the body of the brick itself. These supports are preferably formed integral with the bricks themselves and project from the surface thereof in the form of tongues of lesser sectional 30 area than the surface area of the brick. By this construction a space or a series of intercommunicating spaces is afforded between the surface of the brick lining and the inner surface of the metallic shell, and the said 35 space is shown as filled with a cementitious material in fluid state capable of hardening after the space is thoroughly filled. The complete lining then consists of brick and cement, the brick, however, being not only embedded 40 in the cement, but also positively supported by the metallic shell, and it is found that a lining constructed in this way is unaffected by the expansion and contraction of the shell, so that it does not crack when the digester is 45 heated in use. It is not, however, essential to the invention that the said space should be filled with cement, it being practicable to leave the space empty, in which case it is obvious that such acid as may leak through the 50 lining will not be concentrated at any one

point in sufficient quantity to seriously attack the shell, but will be free to become distributed to such an extent as not to seriously injure the shell.

Figure 1 is an elevation, partly in section, 55 of a digester embodying the invention; Fig. 2, a sectional detail thereof; and Figs. 3 and 4, respectively, perspective views of the two forms of bricks which are preferably used in lining the retort.

The digester embodying the invention comprises the metallic shell *a*, provided at one end with an inlet *a*², the construction of the shell and inlet being substantially the same as that heretofore employed in digesters of 65 this class. The said shell in accordance with this invention is provided with a lining *b*, so arranged as to afford a space or series of 70 intercommunicating spaces (indicated at *b*²) between the lining proper and the surface of the shell, into which space a fluid cementitious material capable of subsequent hardening may be poured, the mass of material being shown at *c*, Fig. 2. To afford the said space, there are a series of projecting supports *b*⁵ interposed between the surface of the shell and the surface of the lining proper, the said projecting supports being herein 75 shown as formed integral with the lining-bricks *b*⁶ and being smaller in area than the surfaces of said bricks, so that when the bricks are laid with their edges adjacent to each other to form a continuous lining spaces are afforded, as shown in Fig. 1, between the projecting portions *b*⁵, thus forming the 80 intercommunicating spaces between the inner surface of the lining and the shell, as above stated. It will be seen that by this construction the brick lining is directly supported throughout upon the inner surface of the shell, 85 although such a space or series of spaces is afforded that when the cementitious material is poured in it will permeate from one end to the other of the digester, the result being that when the cementitious material hardens the 90 said digester is lined throughout with a combined brick and cement lining. While it is desirable to fill the said space with cement, as described, the said space may, as stated, be left 95 open, in which event it will obviate the tend- 100

ency of the acid to be concentrated near a leak and will also afford means for occasional tests to ascertain whether or no the brick lining is tight, such tests being readily made by circulating a liquid through the said space, or, if desired, steam, water, or other diluting or neutralizing fluid may be continuously circulated through said space while the digester is in use, so as to cleanse the shell of any acid 5
 10 which may leak through the lining. For this purpose the space, if left open, may be provided with inlets and outlets b^3 , as shown, it being obviously immaterial whether the inlets and outlets are present or not when the 15 cementitious material is employed. I do not, however, herein claim this specific construction and arrangement, since it forms the subject of another application, filed by me July 15, 1898, Serial No. 686,015.
 20 To assist in the circulation of the acid or other fluid which is admitted to the digester to reduce the wood, the shell is shown as provided with a supplemental inner lining d , provided with a passage d^2 , having inlets and 25 outlets d^3 , communicating with the interior of the retort, so that the fluid admitted to said retort can circulate freely through said passage from one end of the retort to the other and permeate the material therein from both 30 ends, thus hastening the action and rendering it more uniform throughout the mass. To obtain the said inner lining and at the same time to supplement the lining proper and assist in preventing leakage therethrough, 35 bricks are preferably used, said bricks being formed, as best shown in Fig. 4, with two surface portions d^4 of equal area connected together by body portions d^5 of lesser area, so that when the said bricks are laid with their 40 edges adjacent, as shown, there are two continuous lining-surfaces and a passage between them around the body portion d^5 to afford means for circulating the fluid. The inlets and outlets to the said passage may be afforded by 45 making holes in the inner surfaces of some of the bricks, as best shown in Fig. 4, the said holes being indicated by the reference-letter d^6 . These inner lining-bricks may be arranged to break joints with the outer lining-bricks, so as to obviate as far as possible the 50 tendency of the acid to leak through the lining, although the cementitious material, if used, will tend to correct defects in the brick portion of the lining, while if this material is 55 not used such acid as may leak through can be washed away, as hereinbefore described, before it can materially injure the metallic

shell, and in any event will not collect and remain where the leak occurs.

While the construction herein shown and 60 described is simple and efficient, it is not intended to limit the invention to such specific construction, since it may obviously be departed from without departing from the invention. 65

I claim—

1. A retort comprising a metallic shell and a lining therefor composed of bricks, each of which has a portion of its surface directly supported on a portion of the shell, the portion of surface in contact with the shell being smaller than the main surface, whereby intercommunicating spaces are afforded between the bricks and the shell; and a filling of cementitious material in said spaces, substantially as described. 75

2. A retort comprising a metallic shell and a lining therefor composed of bricks having projecting portions of lesser area than that of the main surface of the bricks and being 80 laid with their main surfaces adjacent to each other and their projecting portions in contact with the inner surface of the metal shell; and a filling of cementitious material in the space between said bricks and said shell, substantially as described. 85

3. A digester comprising a metallic shell and a lining of acid-resisting material, a space between said shell and said lining separated from the interior of the digester-chamber, 90 and a circulating-passage within the said lining in communication with the said chamber for the better distribution of the agents admitted to the chamber to act on the material therein, substantially as described. 95

4. The herein-described lining for a digester, comprising a series of bricks each having a projecting portion of smaller area than that of its face portion, the said face portions being laid side by side to afford a continuous lining-surface, and a series of other bricks having two face portions connected together by a body portion of lesser diameter than that of said face portions, the said bricks being laid with their face portions adjacent to each other and 100 one set of face portions in contact with the other bricks, substantially as described. 105

In testimony whereof I have signed my name to this specification in the presence of two subscribing witnesses.

FRED W. AYER.
